UNITED STATES PATENT OFFICE.

JAMES S. REID, OF CLEVELAND, OHIO.

SNUBBER.

Application filed January 28, 1925. Serial No. 5,266.

This invention relates to improvements in what are known as snubbers or shock absorbers which are adapted for use upon automobiles and the like to prevent the objectionable rebound.

The objects of the present invention are to provide an improved snubber or shock absorber which is efficient and altogether dependable in its action and at the same time can be manufactured at comparatively low cost; and to provide such a device which has an operation similar to that of the well known band brake and which is practically free of noise and which is applied in its snubbing action in a gradual manner without any undue jar.

The present form of snubber is adapted to be installed between the frame of the car or other vehicle and the axle and may be installed at either the front or back or at both ends thereof.

Other objects will appear from the following description and claims when considered together with the accompanying drawings.

Fig. 1 is a view showing my improved device in elevation with the cover or one side wall of the drum removed; this view being taken on line 1—1, Fig. 2; Fig. 2 is a plan view of the same with parts broken away; and Figs. 3, 4, 5 and 6 are detail views taken on lines 3—3, 4—4, 5—5 and 6—6 respectively, of Fig. 1.

This improved form of snubber is connected to the frame at a point somewhat forward of a point just above the axle, although of course this particular arrangement may be varied. In the present case, the general direction of the device is shown as extending parallel with the frame of the car, although it might preferably be arranged so as to extend downwardly and rearwardly from a point on the frame approximately just above the axle.

According to the present invention, the drum 1 is fixedly secured to the frame 2 by means of the bolt or post 3 which has the nuts 4 and 5 engaging the frame and the drum 1, respectively. The post 3 is provided with a non-circular portion 6 intermediate its ends and adapted to engage in a correspondingly shaped opening in the plate 7 which in turn has the tongue 8 engaging the lower part of the frame. The non-cir-

cular portion 6 engages also in a correspondingly shaped opening in the one wall of 55 the drum 1 and with this arrangement the drum is prevented from turning. Extending above the drum 1 there is provided the brake band 9 with its lining 10 of suitable fibrous material similar to that used for lining the well known automobile brake bands. The brake band and lining are both slotted, as indicated at 11, to receive the ear 12 on the drum itself, this arrangement constituting a means of centering the band on the drum. 60 The one end of the brake band is anchored at the point 13 to the arm 14 which in turn is freely mounted upon the post 3. By means of the spring 15, one end of which is secured to the post 16 carried by the drum 70 and the other end of which is secured to the post 17 on the arm 14, there is created a tendency for the arm 14 to move upwardly about the post of the drum so as to maintain the taut condition at the cable 18 which is secured at its one end to the arm 14 and at its other end to the axle 19 of the automobile. The other end of the brake band is anchored at the point 20 to the arm 21 which is also freely mounted upon the post 3, and 75 which is under the influence of the spring 21^a anchored at its one end to the post 22 of the drum and at its other end to the post 23 carried by the arm 21. Both of the springs 15 and 21^a are coiled about the post 3. The 80 arm 14 extends through a slot 24 in the drum, this slot being of sufficient extent to permit the necessary movement of the arm 14 in the manner which will be later explained. The arm 21, however, is mounted 85 upon the outside of the drum and is provided with the wings 25 which have apertures 26 sufficiently large to permit free passage therethrough of the adjustable screw 27 which has threaded engagement with the 90 arm 14. The screw 27 may be adjusted in the arm 14 and located in said position by means of the lock nut 28. The screw 27 is provided also with the head 29 and the contact nut 30 with its lock nut 31, these parts 100 being adapted to effect contact engagement between the arm 14 and the arm 21 in the manner to be explained.

The operation is as follows. Upon compression of the spring of the automobile or 105 other vehicles due to sudden lowering move-

ment of the body of the car upon striking a hole in the road, the drum of my improved device will move downwardly with the frame and will at the same time carry with it the arms 14 and 21 which are mounted thereupon. By virtue of the spring 15, which tends to move the arm 14 upwardly, the cable 18 will be maintained in taut condition; and by virtue of the spring 21^a the 10 arm 21 will tend to follow the arm 14 so as to maintain these parts in contact and thereby prevent objectionable noise. The brake band will at the same time be maintained in snug position about the drum. 15 Then when the springs of the automobile are released and the body of the car begins to move upwardly with what would otherwise result in the familiar objectionable rebound, the initial upward movement of the drum, 20 which of course follows upwardly with the car frame, will cause relative effective downward movement of the arm 14 with the consequent effective downward pull upon the end 13 of the brake band so as to gradually 25 tighten the same about the drum and effect the initial snubbing action. Then when there has been sufficient movement of the arm 14 to cause the contact nut 30 to engage the ear 25 of the arm 21 and at the same 30 time to cause the head 29 to engage the lower wing 25, the arm 21 will also be given a relative downward movement together with the arm 14. This combined relative downward movement of the two arms 14 and 21 35 together will cause both ends 13 and 20 of the brake band to move about the drum in a clockwise direction, as viewed in Fig. 1 of the drawings, so that the brake band will be slipped bodily about the drum after having 40 already been effectively tightened by the initial relative downward movement of the arm 14 alone. Such bodily slipping movement of the brake band about the drum produces an effective snubbing action so as to 45 prevent the objectionable rebound and permits the car frame with the body to move upwardly in a gradual manner and at the same time without any sudden shock which might otherwise be caused by a sudden 50 checking of the upward movement of the car frame.

By adjustment of the nuts 28, 30 and 31, the exact point when the arm 21 will be moved together with the arm 14 in the manner just now described can be varied according to the conditions of the springs of the car as well as other prevalent conditions which have to do with rebound action. Thus it will be seen that I have provided an effective device for checking or snubbing the objectionable rebound and have provided a device which possesses the well known and effective brake band action, without however, requiring an unduly great length of brake band and lining. In this way I have been

able to reduce the cost of manufacture of such a device, considering the initial cost as well as the cost incident to renewal of lining as may be necessary from time to time. Another advantage resides in the quietness of 70 the device, as well as the smoothness due to the gradual manner of operation of the present form of device.

It is to be understood that the present 75 showing is only for purposes of illustration and that the structure here shown may be varied according to the principle of the present invention as herein set forth.

What I claim is:

1. A shock-absorbing device for vehicles, 80 comprising a drum adapted to be fixedly mounted upon the vehicle frame, a brake band surrounding said drum, and means including a plurality of arms mounted for co-operative movement about the axis of the drum and actuated by rebound tendency to cause the band to be tightened about the drum.

2. A shock-absorbing device for vehicles, 90 comprising a drum adapted to be fixedly mounted upon the vehicle frame, a brake band surrounding said drum, and means including a plurality of arms mounted for co-operative movement about the axis of the drum and actuated by rebound tendency to cause the band to be tightened about the drum, said arms having limited approach 95 to cause the band to thereafter slip bodily along the drum.

3. A shock-absorbing device for vehicles, 100 comprising a drum adapted to be fixedly mounted upon the vehicle frame, a brake band surrounding said drum, and means including a plurality of spring-pressed arms mounted for co-operative movement about the axis of the drum and actuated by rebound tendency to cause the band to be tightened about the drum. 105

4. A shock-absorbing device for vehicles, 110 comprising a drum adapted to be fixedly mounted upon the vehicle frame, a brake band surrounding said drum, and means including a plurality of arms mounted for co-operative movement about the axis of the drum and having an inter-locking relation 115 for causing said band to slip bodily about the drum in response to rebound tendency.

5. A shock-absorbing device for vehicles, 120 comprising a drum adapted to be fixedly mounted upon the vehicle frame, a brake band surrounding said drum, a plurality of arms mounted for movement about the axis of said drum and having the two ends of said band attached thereto respectively, and operative connections between said arms and the vehicle axle, whereby rebound tendency 125 causes effective engagement of the band about the drum.

6. A shock-absorbing device for vehicles, 130 comprising a drum adapted to be fixedly

mounted upon the vehicle frame, a brake band surrounding said drum, a plurality of arms mounted for movement about the axis of said drum and having the two ends of

5 said band attached thereto respectively, a flexible connection between one of said arms and the vehicle axle, and an operative con-

nection between said arms, whereby tightening of the band about the drum is automatically effected in response to rebound ¹⁰ tendency.

In testimony whereof I hereby affix my signature.

JAMES S. REID.
